UNITED STATES PATENT OFFICE.

CHRISTIAN HANSEN, OF DAVENPORT, IOWA.

LOCK.

1,095,500.

Specification of Letters Patent.

Patented May 5, 1914.

Application filed August 15, 1913. Serial No. 784,886.

To all whom it may concern:

Be it known that I, CHRISTIAN HANSEN, who have declared my intention of becoming a citizen of the United States, residing at 5 Davenport, in the county of Scott and State of Iowa, have invented certain new and useful Improvements in Locks, of which the following is a specification.

My invention relates to improvements in 10 locks of the type, wherein a bolt is moved by a key-cylinder, mounted within a casing, and normally held against turning movement by tumblers, which are moved to their releasing positions by the insertion of a 15 proper key within the opening of the key cylinder.

An important object of this invention is to provide a lock of the above mentioned character, which may be readily operated 20 by a key inserted from either end of the same upon the key being inverted when withdrawn from one end of the key-hole before being inserted within the opposite end thereof.

25 A further object of my invention is to provide a lock of the above mentioned character, which will be very difficult to fraudulently operate.

30 A further object of my invention is to provide a lock of the above mentioned character, which is simple in construction, cheap to manufacture, strong and durable.

Other objects and advantages of this 35 invention will be apparent during the course of the following description.

In the accompanying drawings forming a part of this specification and in which like numerals are employed to designate like parts throughout the same, Figure 1 is a 40 central longitudinal sectional view through the lock, Fig. 2 is a transverse section, taken on line 2-2 of Fig. 1, and looking in the direction of the arrows, Fig. 3 is an end elevation of the outer casing taken on line 3-3 45 of Fig. 1, Fig. 4 is an elevation of one end of the key-hole cylinder, Fig. 5 is a similar view of the opposite end thereof, and, Fig. 6 is a side elevation of the same.

In the drawings wherein is illustrated a 50 preferred embodiment of my invention, the numeral 7 designates an outer casing, which is ordinarily stationary, having a main central opening 8, to receive a key cylinder 9,

which has a key-hole or opening 10 extending longitudinally therethrough from end 55 to end. This key cylinder is preferably formed in two longitudinal parts 9', as shown. The parts 9' are provided with interfitting tongues and grooves 9", as shown. The key cylinder 9 is cylindrical throughout 60 the greater portion of its length and is provided with end polygonal portions 12', carrying reduced cylindrical extensions 13', adapted to rotate within openings formed in side plates 14', as shown. 65

One side wall of the key-hole 10 is provided with a longitudinally extending rib 11, which extends toward a longitudinally extending recess 11'. The rib 11 is adapted for insertion within a longitudinal groove 70 12 formed in the shank 13 of a key 14, as shown. The key is adapted to be inserted within either or both ends of the key cylinder 9 for operating the tumblers, to be described. When the key 14 is inserted in the 75 right end of the key hole 10, (the end shown in Fig. 3), the same will assume the position shown in Fig. 1, but when inserted into the left end of the key-hole 10, it is obvious that the key must be inverted, so that the 80 rib 11 may enter the slot 12. It is to be understood that the shape of the key-hole may be changed if desired, with a corresponding change in the shape of the key, in cross-section. 85

The numerals 15, 16, 17 and 18 designate tumblers, disposed within openings 15' formed in the outer casing 7, the same being held therein by slides 16', as shown. These tumblers control the turning or rotation of 90 the key cylinder 9. The tumblers 15 and 16 are identical and the tumblers 17 and 18 are identical, whereby the key will operate the same when being inserted from either or both ends of the key cylinder. 95 The shank 13 if the key is provided with bittings 19 and 20, disposed near the opposite ends of the shank upon the opposite longitudinal edges thereof, such bittings being identical and serving to operate the tumblers 15 and 16 respectively when the key is inserted through the right end of the key-hole cylinder 9, and operating the tumblers 16 and 15 respectively when inserted through the opposite end thereof. The 100 shank 13 is provided near its opposite ends 105

and upon opposite longitudinal edges thereof with bittings 21 and 22, which are identical and are adapted to operate the tumblers 17 and 18 respectively when inserted 5 through the right end of the key-hole cylinder 9, and to operate the tumblers 18 and 17 respectively, when inserted through the opposite end thereof.

Each of the tumblers comprises radial inner and outer pins 24 and 25, which are longitudinally movable and are arranged in end to end relation, as shown. Surrounding the pins 24 and 25 are intermediate sleeves 26 and 27 respectively, having slideable engagement therewith and arranged in end to end relation. Surrounding the intermediate sleeves 26 and 27 are outer sleeves 28 and 29, slidably engaging therewith and arranged in end to end relation. 10 The radial inner pin 24 and the sleeves 26 and 28 of each tumbler, upon the insertion of the key 14, are moved outwardly the proper distance so that their outer ends come into registration with the periphery 15 of the key cylinder 9, whereby the latter may be turned. In each tumbler, the pin 25 is forced inwardly by a spring 30, the sleeve 27 by a spring 31, and the sleeve 29 by a spring 32, as shown. The spring 31 engages a cup-shaped casing 30', receiving the outer end of sleeve 27, which is engaged by the spring 31. This spring 31 is mounted upon a headed pin 31', arranged within the cup-shaped casing 30', as shown. 20

It is not desired to restrict the invention to any particular shape of bittings, as the same may be varied as may be found advantageous, it sufficing that these bittings that are arranged adjacent the opposite ends 25 of the key shank and upon opposite longitudinal edges thereof, be identical.

The bolt or bolts (not shown), are operated by suitable means (not shown) which are preferably mounted upon the polygonal 45 end portions 12' of the key-cylinder 9. The bolt or bolts, however, may have operative connection with the key-cylinder by any other suitable means.

In the operation of the lock, the key is 50 inserted through either end of the key-hole 10 and will serve to operate the tumblers so that they will release the key cylinder 9, thus allowing the same to be rotated or turned. This key cylinder operates the bolt or bolts (not shown) as is customary in locks of this type.

It is to be understood that the form of my 55 invention herewith shown and described, is to be taken as a preferred example of the same, and that various changes in the shape, size and arrangement of parts may be resorted to without departing from the spirit of the invention or the scope of the subjoined claims.

Having described my invention, I claim:— 65

1. A lock of the character described, comprising in combination a casing having a main opening, a key cylinder rotatably mounted therein and provided with a key hole extending through both ends thereof, 70 tumblers arranged upon opposite sides of the key cylinder to normally prevent its rotation, a key adapted for insertion through either end of the key-hole and provided upon opposite edges with identical bittings 75 which are diagonally arranged and adapted to operate the tumblers upon the insertion of the key into the key-hole and the inverting of the same after being drawn out of one end of the key-hole and before being inserted into the opposite end thereof, and means for necessitating the inverting of the key before inserting it into one end of the key-hole upon removing it from the opposite end of the key-hole. 80

2. A lock of the character described, comprising in combination a casing having a main opening, a key cylinder rotatably mounted therein and provided with a key-hole extending through both ends thereof, 90 pairs of tumblers longitudinally spaced with relation to the key cylinder and arranged near opposite sides thereof, the tumblers in each pair being dissimilar and the tumblers in different pairs arranged upon 95 opposite sides of the key cylinder being identical and longitudinally spaced, a key adapted for insertion through both ends of the key-hole and provided with pairs of longitudinally spaced bittings formed upon 100 the longitudinal edges thereof, the bittings in the same pair being dissimilar and the bittings in one pair being identical with the biting in the other pair arranged upon the opposite longitudinal edge of the key 105 whereby the bittings will operate all of the tumblers when inserted through one end of the key-hole and through the opposite end thereof upon being inverted, and means for necessitating the inverting of the key before 110 the same can be inserted into one end of the key-hole after being inserted in the other end thereof.

3. In a lock of the character described, a casing provided with an opening, a key cylinder rotatably mounted therein, a tumbler associated with the casing and key cylinder, comprising a plurality of outer sleeves arranged in end to end relation, a cup-shaped casing, a compressible coil spring between 115 the cup-shaped casing and one of the outer sleeves, a plurality of intermediate sleeves arranged in end to end relation within the outer sleeves to reciprocate therein with one intermediate sleeve passing over the compressible coil spring and extending into the cup-shaped casing, a compressible coil spring arranged within the cup-shaped cas- 120 125

ing and engaging the last named intermediate sleeve, a plurality of pins mounted to reciprocate within the intermediate sleeves, a headed pin mounted within the cup-shaped casing and having the coil spring therein surrounding it, and a coil spring arranged between the headed pin and one of said pins.

In testimony whereof I affix my signature in presence of two witnesses.

CHRISTIAN HANSEN.
